UNITED STATES PATENT OFFICE.

WILLIAM A. McCOOL, OF PERRYVILLE, ASSIGNOR OF ONE-HALF TO PAUL OLIVER, OF ASHLAND COUNTY, OHIO.

METHOD OF FORMING GROOVED METAL RODS.

SPECIFICATION forming part of Letters Patent No. 328,797, dated October 20, 1885.

Application filed February 10, 1885. Serial No. 155,520. (No model.)

To all whom it may concern:

Be it known that I, WILLIAM A. McCool, of Perryville, in the county of Ashland and State of Ohio, have invented certain new and useful Improvements in Metal Rods; and I do hereby declare the following to be a full, clear, and exact description of the invention, such as will enable others skilled in the art to which it pertains to make and use the same.

10 My invention relates to metal rods, the object being to provide a metal rod with a continuous longitudinal groove by drawing a blank of peculiar construction through a former.

15 The invention consists in forming a grooved metal rod by drawing a semi-elliptical blank through a suitable former, as hereinafter described.

In the drawings, Figure 1 represents, partly 20 in elevation and partly in section, an apparatus for forming the rod. Fig. 2 is a view of the former detached, and Fig. 3 illustrates the blank and partially-formed rod. Fig. 4 shows a cross-section of the blank.

25 A represents a former consisting of a metallic plate having a round opening, B, into which projects a lug, C.

The former A may be combined with any

suitable drawing apparatus, that shown in Fig. 1 being an ordinary wire-drawing machine, and forming no part of my invention.

D represents a blank which is semi-elliptical in cross-section. The edges of the blank are bent toward each other by drawing the blank through the former A, thus forming the groove E throughout the length of the rod.

The grooved rod thus formed is adapted for a variety of purposes. I design to employ it as a frame for street-lamp signs, the groove serving to hold the letters of the sign; but I do not limit myself to any particular application of the rod thus described, as it will be found adapted for a number of purposes.

What I claim is—

The method herein described of forming a 45 drawn grooved rod consisting in drawing a blank semi-elliptical in cross-section through a former to bend up the edges of said blank to form the groove, substantially as set forth.

In testimony whereof I have signed this 50 specification in the presence of two subscribing witnesses.

WILLIAM A. McCOOL.
